MERCURY OINTMENT.

1,384,863.

Specification of Letters Patent. Patented July 19, 1921.

No Drawing.

Application filed January 24, 1920. Serial No. 353,617.

To all whom it may concern:

Be it known that I, JOHN P. SHEPHERD, a citizen of the United States, and a resident of the city of Chicago, in the county 5 of Cook and State of Illinois, have invented certain new and useful Improvements in a Mercury Ointment; and I do hereby declare that the following is a full, clear, and exact description of the same.

10 This invention relates to mercury ointments for the treatment of sores and as an antiseptic agent.

The principal object of the invention is to provide an improved vehicle for the metallic mercury to aid its application to and 15 as far as possible its penetration into the skin and tissues.

One of the most suitable substances for this purpose is cholesterin, since among 20 other properties, it is very readily absorbed by the skin.

In preparing the ointment the metallic mercury is ground with or otherwise emulsified in the cholesterin to form a smooth 25 paste. Preferably about equal parts of mer-

cury and cholesterin are employed, but this ratio may be varied through a wide range to suit differing conditions.

If desired additional ingredients may be incorporated in the ointment such, for example, as petrolatum to increase the unguent and other desirable properties of the ointment.

I claim as my invention:

1. An ointment comprising mercury and a vehicle consisting chiefly of free cholesterin. 35
2. An ointment comprising substantially equal parts of metallic mercury and free cholesterin.
3. An ointment including mercury, free cholesterin, and an unguentary agent. 40
4. An ointment including mercury, free cholesterin, and petrolatum.

In testimony whereof I have hereunto subscribed my name in the presence of two 45 subscribing witnesses.

JOHN P. SHEPHERD.
